PRINTING MACHINE

Jesse D. Klopfenstein, Fort Wayne, Ind., assignor
to Colorgraphic Process Corporation, a cor-
poration of Illinois

Application March 1, 1937, Serial No. 128,370

10 Claims. (Cl. 101—123)

The invention relates to printing machines and it is particularly directed to machines adapted to apply paint through stencil screens.

In a copending application for a printing machine wherein paint is applied through stencil screens, the screen is held stationary and the sheet to be imprinted is fed by a carrier onto a platen which raises the sheet into contact with the screen. A reciprocating squeegee forces the 10 printing material, which is generally a form of paint, through the screen onto the sheet.

I have found it to be important that the imprinted sheet shall readily separate from the screen as the platen lowers at the completion of 15 the stroke of the squeegee and be carried from the platen so to permit the next sheet to engage the platen. Some paints, such as enamel or lacquer, cause the sheet to cling more or less to the screen so that their separation is retarded and 20 blurring of the imprinted matter frequently occurs.

The object of the present invention is to provide a stencil printing mechanism with means by which the separation of the imprinted sheet 25 from the stencil is effected with rapidity and blurring of the imprinted matter is avoided.

Another object is to provide a rocking stencil screen support for the machine.

Figure 1 is a side elevation of a machine embodying the invention.

Fig. 2 is a plan view of the screen-carrying frame.

Fig. 3 is a side elevation of the said frame.

Fig. 4 is a cross section on line 4—4 of Fig. 3.

Fig. 5 is an end view of the squeegee and side elevation of the operating mechanism therefor.

Fig. 6 is a cross-section on line 6—6 of Fig. 5.

Fig. 7 is a plan view of the timing gear assembly.

Fig. 8 is a cross section on line 8—8 of Fig. 7.

Fig. 9 is a front view of the mechanism for the conveyor.

Fig. 10 is a side elevation of said mechanism.

Fig. 11 is a plan view of the machine with the 45 squeegee and screen mechanisms removed and illustrating the table or platen.

Fig. 12 is a cross section of the table or platen on line 12—12 of Fig. 11.

Fig. 13 is a side view of the alining and locking mechanism for the cross-bars of the conveyor, and

Fig. 14 is a side view of one of the retaining band supports, and Fig. 15 is an edge view partly in section of a part of the squeegee recipro- 55 cating mechanism.

Referring to the illustrative drawings, the main frame of the machine is marginal in character and is formed of corner upright members 1, longitudinal top rails 2, lower rails 3 and a suitable number of transverse rails or beams 4 5 for rigidity. The top of the machine may be covered except in its central portion where an opening is formed to receive the table or platen 6 (Figs. 11, 12) that is supported on two arms 7 at the opposite sides thereof, the arms being 10 pivoted at their forward or free ends at 8 to the main frame. A link 9 (Fig. 1) is connected to the lower side of the table 6, a second link 10, pivotally connected to the link 9 and to the frame-member 3, forming a toggle to which the 15 link 11 is connected. The latter link is connected to the link 12 which is connected to a lever 13 carrying a roller 14 that bears on a cam 15 mounted on the main drive shaft 16, by all of which the table is rocked on its pivots.

The top wall 17 of the table (Fig. 11) is perforated and a wall 18 cooperates with the wall 17 to form a suction chamber between them to which a conduit 19 is connected. The conduit leads to a pump 20, a valve 21 being interposed 25 in the conduit and operated by a lever 22 which is rocked by a cam 23 mounted on the main shaft 16. The pump is driven in any suitable manner. In Figs. 11 and 12, for clearness, the conduit 19 is shown as leading forwardly from the central 30 portion of the table. In practice, the conduit will so lead from the table to the pump that it will not interfere with the movement of the conveyor that consists of two chains 24 and a series of gripper-carrying bars 25 each of which is attached at its opposite ends to the chains respectively.

The conveyor chains engage the rear sprocket wheels 26 and the sprocket wheels 27 mounted on a shaft 28. A sprocket wheel 29 on the shaft 40 28 is engaged by a chain 30 which passes over an idler sprocket 31 and is driven by the sprocket wheel 32, mounted on a spindle 33, Fig. 7, and driven intermittently by the gear 34 of a set of timing gears 34, 35 and 36.

In order to check the movement of the conveyor after each revolution of the gear 34, I mount a member 37, Fig. 10, on the shaft 16 and pivotally mount thereon two pairs of arms 38, 39. Each pair of arms supports an angle bar 40, 41 50 at their outer ends, the bars being on corresponding sides of the arms. Springs 42 oppose outward movement of the arms and the stops 43 limit the inward movement of the arms. The bar 40 is shown as contacting a gripper bar 25 55

and it tends to snub the conveyer as the gear 34 stops. The bar 40 moves downwardly and the bar 41 moves upwardly, as shown in broken lines, into the path of the next gripper bar 25 and starts the movement of the conveyer as the gear is again set in motion. Jerking and jarring of the conveyer is thereby avoided.

On the top longitudinal members of the main frame and at opposite sides of the table are mounted the racks 44 which are adapted to be engaged by the curved racks 45 mounted on the curved screen-carrying support 46, Figs. 2, 3. The stencil screen is stretched on a frame 47 that is capable of conforming to the curvature of the support and secured thereto. A bracket 48 is secured to the support 46 and is connected by the link 49 eccentrically to the gear 51 that is driven by the timing gears. As the gear 51 rotates, its motion, through the link, causes the screen-carrying support to rock to and fro on the racks 44 so that the screen, as it were, is peeled off the imprinted sheet on the table beneath it. The imprinting material is applied to the stencil screen by the squeegee mechanism 52, Figs. 5, 6.

The squeegee mechanism consists of two blades 53, 54 mounted on a frame 55 and projecting in opposite directions with respect to the longitudinal axis of said frame. The arms 56 depend from the opposite ends of the frame 55 and the studs 57 are mounted in the lower ends of the arms respectively. The plates 58 are mounted on the studs and their upper ends embrace the opposite edges of the arms 56 respectively. Two other arms 59, 60 are secured to the opposite ends of the frame 55 each having a pin 61 projecting therefrom that is adapted to engage in a cam slot 62 formed in the adjacent plate 58. A second slot 63 is formed in the arm 59 and receives the adjacent stud 57. A cam 64 is formed on the lower end of the arm 59 and is adapted to be engaged alternately by the abutments 65 mounted on a slideable bar 66. A link 67 connects the bar to a sprocket wheel 68 that is intermittently driven through the chain 69 by a sprocket 70 mounted on the spindle 33 of the timing gear 34. The rotating sprocket 68 causes the bar to reciprocate intermittently which causes the abutments to rock the squeegee frame for alternately engaging the blades with the screen.

The links 71 are mounted on the studs 57 respectively and are pivotally connected to the levers 72 mounted at their lower ends on a shaft 73 to which a crank 74 is secured. A link 75 connects the crank to the crank 50 that is mounted eccentrically on the gear 51 by which oscillation of the lever is effected to reciprocate the squeegee frame with the blades in contact alternately with the screen. The tripping bar 66 is so timed in its movements that at the end of a stroke of the squeegee frame the abutment then engaging the cam 64 on the arm 59 is caused to rock the frame so as to engage the idle squeegee blade on the screen. Each squeegee blade follows the curvature of the screen as it travels from one end of it to the other and forces the imprinting material deposited on the screen through the same onto the sheet to be printed.

A segment rack 76 is intermittently rocked in opposite directions by the crank 74 and is engaged by a segment gear 77 revolvably mounted on the bracket 78 that supports the shaft 73. A link 79 is pivotally connected at its upper end to an arm 80 which is secured to the plate 58 of the squeegee frame, a similar arm being similarly

connected to the other plate 58. The lower end of each link 79 is pivoted to a crank 81 secured to the shaft of the gear 77. When the crank 74 is rocked downwardly to rock the lever 72 rearwardly, or to the right, Fig. 1, the rack 76 rocks to the right and causes the gear 77 to turn to the left. The crank 81 is thereby rocked downwardly and draws down on the link 79 whereby the arm 80 is maintained in substantially a straight line as the lever 72 reciprocates the squeegee mechanism rearwardly. The upward movement of the crank 74 reverses the movement of the several connections to the squeegee mechanism and causes it to move forwardly. The links 79 again tend to maintain the arms 80 in a horizontal position.

A bar 82, one at each side of the squeegee frame and spaced vertically from the roller 83 mounted on the end arms 56, is pivoted at its lower end to a linkage 84 which connects to a pedal 85. The forward end of the bars 82 carry pins 86 which slide in the slots 87 formed in the plates 88 mounted on the main frame. By rocking the pedal the bars 82 are caused to engage the rollers 83 and elevate the squeegee frame so that neither squeegee blade will contact the screen and force any of the imprinting material through the screen onto the material deposited on the table by the conveyer or onto the table if no material has been brought to the table by the conveyer.

In order to further assure the ready separation of the screen from the imprinted material, I attach the ends of a band 89 to the brackets 90 which are slidably mounted on the rods 91 supported by the flanges 92 on the opposite top members of the main frame. The band is adapted to contact the sheet of material that is carried by the conveyer under the screen and raised into contact with the screen and band by the table. The band, of course, will be adjusted on the rods 91 so that it will contact the sheet without interfering with the area thereof to be printed. After the sheet is printed the table lowers and the conveyer removes the sheet, and another sheet takes its place, the conveyer traveling in the direction of the arrow, Fig. 11.

In order to align each gripper bar 25 so that the sheet of material carried by it will be in registration for imprinting, I revolvably support a shaft 95 on the table supporting arms, 7, Figs. 11, 12, 13, at a suitable point forwardly of the table and secure thereto a suitable number of fingers 96. A depending arm 97 is secured to the shaft 95 and a spring 98 is connected to the arm and to the table structure and opposes forward swinging movement of the arm relatively to the forward end of the table. To each end of the shaft 95 is secured a member 99 having an arm 100 carrying an adjusting screw 101. The members and their arms are located below the bottom flange of the main frame members 2 so that as the table rises the adjusting screws will eventually and at the proper time abut the said flanges of members 2 and cause the shaft 95 to turn clockwise thereby swinging the fingers 96 to a vertical position. By the time this movement of the fingers begins the approaching gripper bar has or is about to come to rest adjacent to the forward edge of the table. The fingers abut the bar and move it into engagement with the forward end of the table thereby assuring that the sheet conveyed by the bar is properly located on the table for registration with the screen.

The grippers 25 on the bars 25 are opened

and closed in any convenient manner as each bar arrives at the feed table 93, and they are again opened and closed at the discharge end of the machine to release the printed sheet.

5. The main shaft is driven by the electric motor 5 or other source of power, through a belt and the pulley 5'.

What I claim is:

1. In a printing mechanism, a rocking stencil screen, a movable table below the screen and adapted to elevate sheets of material successively for rocking contact by the screen, means to temporarily retain each sheet on the table and a reciprocating mechanism to force imprinting material through the screen onto the sheets, said mechanism including an oscillating frame, a pair of squeegees supported by the frame, the members of the pair being declined in opposite directions and means to cause said squeegees to alternately engage the screen and comprising a member depending from the frame and a pair of reciprocable abutments adapted to be alternately engaged by said latter member at the completion of the strokes of the mechanism respectively.

25. 2. In a stencil-screen printing machine, an arcuate rocking stencil screen, a squeegee mechanism comprising a frame carrying a depending blade adapted to engage the screen, two arms at opposite ends of the frame respectively on which the frame is mounted, a pair of levers having pivotal linked connection with the arms respectively for reciprocating the arms and the frame, a pair of members rigidly secured to the arms and projecting forwardly therefrom, links connected to the members and means to cause the latter links to move in a direction opposite to that of the levers whereby the frame is caused to reciprocate in substantially a straight line.

3. In a printing machine, a stencil screen, a table movable toward the screen, a conveyer to intermittently carry sheets of material to the table successively and including a series of transverse gripper bars, each bar coming to rest forwardly of the table and means to positively aline each gripper bar with the table and comprising a rock shaft carried by the table, upwardly projecting fingers on the shaft, fixed members and means secured to the shaft and adapted to abut the fixed members, as the table moves toward the screen, for rocking the fingers into engagement with the gripper bars and contacting said bars with the forward end of the table.

4. In a printing machine, a main frame, a pair of racks mounted at opposite sides of the top of the frame, a longitudinally curved frame having racks on its lower side adapted to rock in the said racks on the main frame respectively, a main drive shaft, a set of gears having driven connection with the shaft, a link connected to one of the gears and to the curved frame for rocking the frame in opposite directions, a flat stencil screen-carrying frame adapted to be secured to the curved frame and conformed thereto, a squeegee mechanism adapted to travel back and forth on the stencil screen and means to feed sheets of material successively under the screen for rocking engagement thereby.

5. In a printing machine, a table, a conveyer to carry sheets of material successively to and from the table, means to intermittently drive the conveyer, a stencil screen, means to produce relative movement between the table and the

screen for engagement of the sheets by the screen, means to force imprinting material through the screen onto the sheets, means to retard the conveyer at the end of each intermittent movement thereof and means to store up energy which is 5 then utilized to initiate motion in the conveyer at the beginning of each succeeding movement thereof.

6. In a printing machine, a table, a conveyer to carry sheets of material successively to and 10 from the table, means to intermittently drive the conveyer, and means to retard the conveyer at the end of each intermittent movement thereof and to initiate the next succeeding movement thereof and comprising a revolubly mounted member, two 15 members pivotally mounted on the revolubly mounted member and adapted to alternately resiliently contact the conveyer.

7. In a printing machine, a table, a conveyer to carry sheets of material successively to and 20 from the table, means to intermittently drive the conveyer and means to retard the conveyer at the end of each intermittent movement thereof and to initiate the next succeeding movement thereof and comprising a revolubly mounted member, 25 two members on opposite sides of the revolubly mounted member and pivoted to the latter member adapted to alternately engage the conveyer and resilient means opposing the pivoted movement of each conveyer-engaging member in one 30 direction.

8. In a printing machine, a support, a longitudinally curved frame adapted to rock on the support, means to prevent bodily creeping of said curved frame on the support during such 35 rocking movements, a main drive shaft, a set of gears having driven connection with said shaft, a link connected to one of the gears and to the curved frame for rocking the frame in opposite directions, a flat stencil screen-carrying frame 40 adapted to be secured to the curved frame and conformed thereto, a squeegee mechanism adapted to travel back and forth on the stencil screen and means to feed sheets of material successively under the screen for rocking engagement thereby. 45

9. In a printing machine, a support, a longitudinally curved frame adapted to rock on the support, means to prevent bodily creeping of said curved frame on the support during such rocking movements, a main drive shaft, a driving connection between said shaft and the curved frame for 50 rocking the frame in opposite directions, a flat stencil-carrying frame adapted to be secured to the curved frame and conformed thereto, a squeegee mechanism adapted to travel back and forth on the stencil screen and means to feed sheets of material successively under the screen for rocking engagement thereby. 55

10. In a printing machine, a support, a pair of racks mounted on the support, a longitudinally 60 curved frame having racks adapted to rock in the racks on the support, a main drive shaft, a driving connection between said shaft and the curved frame for rocking the frame in opposite directions, a flat stencil screen-carrying frame 65 adapted to be secured to the curved frame and conformed thereto, a squeegee mechanism adapted to travel back and forth on the stencil screen and means to feed sheets of material successively under the screen for rocking engagement thereby. 70
